UNITED STATES PATENT OFFICE

149,025

DESIGN FOR A HAIRPIN OR SIMILAR
ARTICLE

Lester T. Sawyer, Leominster, Mass.

Application April 13, 1946, Serial No. 128,577

Term of patent 14 years

(Cl. D86—10)

To all whom it may concern:

Be it known that I, Lester T. Sawyer, a citizen of the United States of America, residing at Leominster, in the county of Worcester and Commonwealth of Massachusetts, have invented a new, original, and ornamental Design for a Hairpin or Similar Article, of which the following is a specification, reference being had to the accompanying drawing, forming a part thereof.

Fig. 1 is a front elevation of a hairpin embodying my new design;

Fig. 2 is a side elevation of the hairpin; and
Fig. 3 is a rear elevation of the hairpin.

The dominant feature of my design resides in the combination of a pair of slightly convergent, curved outer teeth, each having a scalloped inner edge, with a plain curved intermediate tooth

shorter than the outer teeth and contiguous to the scalloped edges of the outer teeth, all as shown.

I claim:

The ornamental design for a hairpin or similar article, substantially as shown and described.

LESTER T. SAWYER.
